COMBINED SOAP AND TUMBLER HOLDER

Eileen J. Gold, 42 Bank St., New York, N.Y. 10014

Filed July 2, 1975, Ser. No. 592,465

Term of patent 14 years

Int. Cl. D23—02

U.S. Cl. D6—91

FIG. 1.

FIG. 2.

FIG. 3.

FIG. 4.

FIG. 5.

FIG. 7.

FIG. 8.

FIG. 1 is a perspective view of a combined soap and tumbler holder embodying my new design;

FIG. 2 is a top plan view thereof;

FIG. 3 is a front elevational view thereof;

FIG. 4 is a rear elevational view of the soap holder;

FIG. 5 is a side elevational view taken from the left of FIG. 1;

FIG. 6 is a side elevational view taken from the right of FIG. 1, the soap being shown in broken lines magnetically held in place for illustrative purposes only;

FIG. 7 is a bottom plan view thereof; and

FIG. 8 is an exploded rear elevational view, showing the mounting plates in separated condition.

I claim:

The ornamental design for a combined soap and tumbler holder, as shown and described.
